A. L. BALL,
HOVER FOR POULTRY,
APPLICATION FILED JULY 31, 1918.

1,417,225.

Patented May 23, 1922.

UNITED STATES PATENT OFFICE.

ARLINGTON L. BALL, OF DUNKIRK, NEW YORK, ASSIGNOR OF ONE-THIRD TO HARRY C. HEQUEMBOURG AND ONE-THIRD TO GERTRUDE P. HEQUEMBOURG, BOTH OF DUNKIRK, NEW YORK.

HOVER FOR POULTRY.

1,417,225.

Specification of Letters Patent. Patented May 23, 1922.

Application filed July 31, 1918. Serial No. 247,526.

To all whom it may concern:

Be it known that I, ARLINGTON L. BALL, a citizen of the United States, residing at

Dunkirk, in the county of Chautauqua and 5
5 State of New York, have invented certain new and useful Improvements in Hovers for Poultry, of which the following is a specification.

My invention relates to improvements in 10
10 poultry hovers, and more particularly to that type known as "colony" hovers.

The primary object of my invention is the provision of a poultry hover in which heated air is caused to circulate therein, in contradistinction to the usual method of heating 15
15 the interior of the hover by radiation.

Another object of my invention is the provision of a hover of the colony type so constructed that an oil burner or heater may 20
20 be employed and so that the burner or heater is supplied with fresh warm air to assure a steady blue flame.

A further object of my invention is to so construct the hover that while introducing 25
25 fresh air to the chicks and the burner or heater, such air is caused to commingle with the heated air, freed from obnoxious fumes or gases; the hover being arranged to provide a runway for the chicks around a central burner or heater casing.

Still further objects are, to provide a hover of simple construction in which air inlet-pipes leading from the exterior are dispensed with; to so construct the hover to 30
30 enable the burner to be readily removed from the hover; to provide the hover with a gravity fuel supply so arranged that the hover canopy may be removed without detaching said fuel supply.

40 A still further object is, to provide a hover which is economical in operation and easily manipulated, and in which the interior can be made readily accessible.

The invention consists in a hover having a 45
45 suitable burner or heater arranged centrally therein and being constructed so that the heating of the chick space therein is caused mainly by the circulation of heated air through the hover.

50 It also consists in the novel features of construction whereby the canopy curtain is attached to the canopy; in the novel features of construction employed in the remaining parts of the hover; and in the combination

and arrangement of parts as hereinafter set forth and pointed out in the subjoined claims.

In the drawings:—

Fig. 1 is a central vertical section through my improved hover. 60

Fig. 2 is a fragmentary top plan view of the same.

Fig. 3 is an enlarged fragmentary vertical section showing the top or upper central portion of the hover casing and the lower 65 portion of the draft or fume pipe.

Fig. 4 is an enlarged horizontal section taken on line 4—4, Fig. 1.

Fig. 5 is an enlarged section taken radially on line 6—6, Fig. 2. 70

Fig. 6 is a fragmentary top or plan view of the marginal portion of the canopy.

Fig. 7 is a similar view showing the curtain removed therefrom and the formation of the curtain securing prongs before bending the same into hook form. 75

Reference being now had to the drawings in detail, the numeral 8 designates the central burner or heater casing which is arranged vertically and is preferably of cylindrical formation in cross section. This burner or heater casing comprises the cylindrical side wall 9, the bottom 10 and the top 11. The side wall and bottom may be constructed of sheet metal, while I preferably 80 construct the top of cast iron in two pieces, one piece being the fixed part 12 of the top, which has a depending flange 13 adapted to be entered into the upper end of the cylindrical side wall 9 and the other being an 85 open lid or annulus 14 supported by the fixed part 12 and readily removable therefrom. The side wall 9 is provided with one or more air openings 15 over which screening 16 is placed. This burner or heater casing 8 serves as the main support for the remaining parts of the hover. 90

Passed diametrically through the burner or heater casing 8 is a burner supporting-rod 17 which receives support from the side walls at diametrically opposite points and is adapted to support the gas burner 18, said burner being provided with lugs 19 through which said rod is passed. The outer fixed part 12 of the top of said burner or heater 100 casing has its central opening of a size to permit the introduction of the burner there-through or the removal of the burner from 105

the burner or heater casing when removing the annulus or open lid 14, so called by reason of said lid having a central opening 20 which, however, is of smaller diameter than 5 the burner, for a purpose to appear hereinafter.

21 designates the top or flat central portion of the hover casing which is supported from the top of the burner or heater casing 10 by means of spacing sleeves 22 interposed between the two and through which bolts 23 are passed, said bolts being inserted from the under side of the top of said burner or heater casing and extending through the top 15 or central portion of the hover casing, each bolt having a nut 24 applied to its projecting end so as to securely fasten said top or central portion of the hover casing to the burner or heater casing. The central portion 20 of the hover casing comprises two parts or annuli 25, 26, the outer part being the part thereof supported by the burner or heater casing, and the inner part being supported by said outer part and removable 25 therefrom. Said inner part 26 has a central opening 27, for a purpose to appear hereinafter.

The opening in the outer part 25 of the top or central portion of the hover casing is 30 substantially the same size as the opening in the fixed part 12 of the top of the burner or heater casing so that when the open lid or annulus 14 of said last-mentioned top is removed and the inner part 26, which may also 35 be termed an open lid, is removed from the outer part 21 of the top or central portion of the hover casing, the burner 18 may be removed from the hover.

28 designates the canopy which preferably 40 comprises a cast iron ring or annulus 29 adapted to lie against and receive support from the marginal portion of the top or central portion of the hover casing. This annulus has a downwardly inclined flange 30 around its outer edge to which the sheet metal body portion 31 of the canopy is secured. For convenience in shipping, I construct this canopy in four sections 32, 33, 34, 35, joined together by slip joints 36, or in 50 any other suitable manner, so as to form spreading gradually lowering side walls over the chick space 37.

At regular intervals around the marginal 55 portion of the canopy, the sheet metal material is provided with a pair of cut-away portions 38, which are of V-shape and join each other at the edge of the canopy, the two inwardly-diverging sides of these cut-away portions being continued in the form of 60 incisions 39 to points beyond the apices of these cut-away portions, thus providing V-shaped prongs 40, each having the cut-away portions at opposite sides of the outer end thereof. These prongs are adapted to be 65 bent upwardly and inwardly into hook

form, and onto these prongs the flexible curtain 41 of cotton duck, or similar material, is adapted to be attached, the curtain being provided with suitable openings for the purpose, or being forcibly passed over 70 the hook-shape prongs which may be clenched downwardly, as shown in Fig. 5, to assure a secure fastening of the curtain and to prevent the clothing of the attendant catching into the points thereof. 75

The oil burner has a fuel supply pipe 42 connected thereto, which leads upwardly and outwardly through the top of the hover casing to a fuel supply device 43, which may be of any suitable construction, a valve 44 being provided in the supply pipe 42 to regulate the feed of the fuel to the burner. By arranging the fuel supply device at an elevated point, the fuel is fed to the burner by gravity. 80

45 designates a draft or fume pipe which has its lower end entered into a drum 46 provided with a supporting flange 47. The drum 45 is inserted through the opening in the top or flat central portion of the hover casing, or more particularly through the opening in the open lid 26 thereof, and extends into the burner or heater casing through the opening in the open lid 14 of the latter. Said flange 47 rests upon the top 95 or flat central portion of the hover casing and supports said drum and the draft or fume pipe secured thereto and at the same time closes the opening in the top of the hover casing. 100

Between the lower inserted end of the draft or fume pipe 45 and the side or surrounding wall of the drum 46, an intervening space 48 is provided, and a space 49 is also provided between the bottom of said drum and the lower edge of said draft or fume pipe. The side or cylindrical wall of the drum 46 is provided near its upper end with openings 50, and as shown in the drawings the drum is closed at all points except 105 where these openings 50 are arranged. A retarder 51 of dish-like formation is positioned within the draft or fume pipe a short distance from its lower end, it being separated by the wall of said pipe by an intervening space 52 and being secured to the lower end of a rod 53 arranged in said pipe 110 and secured at its upper end to the upper end of said pipe by a bolt 54, or otherwise.

Surrounding the upper end of said draft 120 or fume pipe 45 is a handle 55, which is formed of a strip of metal curved to conform to the curvature of the draft or fume pipe and arranged to almost encircle the same, it being provided with outstanding 125 ends 56 by means of which it may be grasped to remove the draft or fume pipe and the drum 46 carrying the same. For convenience, the handle 55 is secured to the draft or fume pipe by means of the bolt 54, which 130

serves also to fasten the retarder 51 in proper position within said pipe.

By the use of the open lids in the top of the burner or heater casing and in the top 5 of the hover casing, the drum 46 can be reduced in size and the proper size opening provided around the same, while providing for the removal of the burner from the hover without removing the hover casing.

10 This arrangement also provides for the proper quantity of heat to be delivered to the top of the heater casing and furnishes escape through the draft or fume pipe for the lighter products of combustion, such as 15 the fumes and gases, without furnishing too free an escape, which would permit unnecessary quantities of air free from gases and fumes to escape, resulting in increased consumption of fuel.

20 In the flat central portion of the hover casing, a vent opening 57 is formed which is adapted to be closed by a damper valve 58 connected to a lever 59 pivotally secured between its ends, as at 60, to a bracket 61 25 fastened to the canopy 28. The lever 59 is connected to or operatively arranged with respect to a thermostatic device 62 located within the hover casing. When the temperature in the hover casing reaches a pre- 30 determined point, the thermostatic device causes actuation of the lever 59, which in turn lifts the damper valve 58 so as to open the vent opening 57, thus allowing some of the heat to escape through said vent open- 35 ing until the temperature in the hover casing lowers to a predetermined point, where- upon the damper valve closes automatically through the action of said thermostatic device.

40 63 is a thermometer support formed of a strip of metal fastened to the canopy 28, at or near its marginal portion, as at 64, this strip of metal being bent downwardly from the canopy, as at 65, and thence inwardly, 45 as at 66, into the chick space 37 within the hover casing, the curtain 41 being provided with an opening 67 for the purpose. The downwardly bent portion 65 of said thermometer support is also provided with an

50 opening 68 which registers with the openings 67 in said curtain and in said opening a thermometer 69 is placed, the outer end of the thermometer projecting outwardly from said support and having temperature indi- 55 cating graduations thereon, while the inner end thereof projects into the hover casing and is supported on the inwardly-directed portion 66 of said support. This arrangement permits of readily reading the tem- 60 perature within the hover casing without removing or displacing any parts of the apparatus and at the same time positioning the effective portion of the thermometer in close proximity to the space occupied by the 65 chicks, sufficient room only being allowed

between the inner end of the thermometer support 63 and the floor to permit the chicks to pass underneath.

It is to be noted that a space is provided between the lower edge of the curtain 41 70 and the floor so as to admit fresh air to the hover, the space, however, being of a height to prevent the chicks passing out underneath the same.

When it is desired to remove the canopy 75 from the supporting portion of the device it is simply necessary to lift the same upwardly and slightly laterally so as to bring the opening therein in a position to permit of passing the canopy over both the draft or 80 fume pipe and the fuel container of the fuel supply device. It is to be noted that the burner or heater casing and the central portion of the hover casing spaced from the top of the burner or heater casing constitute the 85 supporting member of the hover on which the canopy with its attached curtain is adapted to rest. While the central portion of the hover casing is supported by the burner or heater casing it acts in conjunction with the canopy to retain the heat and deflect the heat downwardly toward the bottom of the canopy casing.

90 In order to ignite the fuel, the drum 46 and the draft or fume pipe 45 are removed 95 from the hover casing by lifting the same out of the central opening in said casing. A small quantity of liquid fuel may then be placed within the burner and a lighted match applied thereto to ignite the same. 100 The valve 43 in the fuel supply pipe may then be opened to permit the feeding of the fuel to the burner from the fuel supply device, which fuel becomes heated and converted into gas, and when escaping from the 105 burner becomes ignited by the burning fuel previously provided. This, however, forms no part of my invention, and the fuel may be supplied and treated in any other way, it simply being a convenient arrangement to 110 ignite the fuel through the top of the hover casing which my particular novel construction permits.

115 The air within the hover casing is heated by contact with the outer surface of the heater casing and this heated air rises and is deflected downwardly by the top or flat central portion of the hover casing and spreads laterally in contact with the inclined wall of the canopy which acts to force the 120 same downwardly to the floor where it meets the inrushing fresh air entering underneath the curtain 41 and furnishes the chicks within the hover casing with fresh heated air. The fumes and gases rising from the burner 125 travel upwardly through the opening 20 in the lid of the heater casing and escape through the openings 50 in the drum 46. These fumes and gases are caused to travel downwardly within the drum 46 by reason 130

of the lower end of the draft or fume pipe extending into the drum and thence pass around the lower end of said draft or fume pipe and out through said pipe, the fumes and gases 5 passing upwardly through the draft or fume pipe. The heated gases passing upwardly through the draft or fume pipe encounter the retarder 51, which is arranged in a plane 10 short distance above the top of the hover casing and thus the free escape of the heat is avoided. Sufficient space, however, is provided around the retarder to allow the escape of the fumes or gases, even though retarded in their upward travel. In this manner 15 the quantity of hot air commingling with the gases is reduced to the minimum and the upper end of the draft and fume pipe remains comparatively cool so that it can be easily handled. If desired, the upper end of 20 the draft or fume pipe may be connected to an escape pipe leading out of the building in which the hover may be located.

The arrangement described provides primarily for the circulation of heated air 25 free, or substantially free, from gases and fumes through the hover casing, so as to keep the chicks therein in a warm and thriving condition, particularly in view of the fact that as this heated air spreads and travels 30 downwardly, it is brought into intimate contact and commingles with the inrushing fresh air passing underneath the curtain, and in commingled condition passes into the heater casing to provide the burner with 35 the proper quantity of fresh air to cause proper combustion. The circulation of the heated air furnishes more heat than can be provided for radiation, with the result that less fuel is consumed to obtain the same 40 results and more perfect combustion is assured.

Having thus described my invention, what I claim is:

1. In a hover, the combination of a central heater casing having an opening in its 45 top wall, a hover casing supported by said heater casing and having a central flat portion and a canopy portion carried by said flat portion and being directed outwardly 50 and downwardly therefrom, said canopy portion having a flexible curtain secured to its edge with the lower edge of said curtain spaced from the floor, a pipe extending centrally through the hover casing, and a drum 55 supported by said hover casing and extending into said heater casing and having openings in its sides at a point above the lower end of said pipe, the lower end of said pipe being spaced from the bottom of said 60 drum.

2. In a hover, the combination of a heater casing having an opening axially in its top wall and being provided with openings in its side, a burner within said heater casing, 65 a hover casing spaced from said heater cas-

ing and supported thereby, said hover casing having an axial opening in its top, a drum passed through the axial openings in said heater casing and said hover casing and having openings in its side near its upper end, and a pipe secured to said drum and having its lower portion extending thereinto with the lower end thereof spaced from the bottom of said drum.

3. In a hover, the combination of a heater 75 casing having a top wall formed in two annular parts fitting one within the other, the inner annular part being removable from the outer part to increase the size of the opening in said top wall, a burner within 80 said heater casing removable through said top wall when removing said inner annular part therefrom, and a hover casing supported by and spaced from said heater casing and having a top formed in two annular parts fitting one within the other, the inner 85 annular part being removable from the outer part to increase the size of the opening in said wall, the whole permitting the withdrawal of the burner from the hover without otherwise disturbing or removing other parts of the hover or heater casings.

4. In a hover, the combination of a heater casing having an axial opening in its top wall and openings in its side, a hover casing having a flat central portion provided with an axial opening and being rigidly supported and spaced from the top wall of 95 said heater casing and a canopy extending downwardly and outwardly from said central flat portion and receiving support from the marginal portion of the latter, a drum supported by said flat central portion and extending through the axial opening of the same and through the axial opening in the top of said heater casing, said drum being 100 spaced from the walls of said axial openings and having openings in its sides near its upper end, a draft pipe having its lower portion fitted into said drum and spaced from the walls of the latter at the sides and bottom, and a burner in said heater casing.

5. In a hover, a canopy having a plurality of pairs of V-shaped notches at intervals around its marginal portion, the inwardly diverging walls of each pair of notches being continued inwardly in the form of incisions to provide outwardly pointed V-shaped prongs, said prongs being adapted to be bent upwardly and inwardly into hook shape, and a curtain connected to said hook shaped prongs.

6. In a hover, the combination of a heater casing having openings in its side and a top formed with two annular parts, the inner annular part having an opening of given size and being removable from the outer part to increase the size thereof, a burner of larger diameter than the opening 125 130

- in said inner part but of smaller diameter than the opening in said outer part and being removable through the top of said heater casing when removing said inner 5 part, and a hover casing supported by the heater casing and spaced therefrom.
7. In a hover, the combination of a heater casing having openings in its side and having a top wall formed of two annular parts fitting one within the other, the outer annular part being rigidly secured to the side of said heater casing and the inner annular part being removable from the outer annular part and having its central opening of 10 a given size, a hover casing having a flat central portion and a canopy extending downwardly and outwardly from said central portion and being supported by the marginal portion of the latter, said flat central portion having two annular parts arranged one within the other, the outer annular part being rigidly supported by the outer annular part of said heater casing and the inner annular part being removable from said 15 outer annular part and having a central opening of a given size, a burner in said heater casing of larger diameter than the central openings in the inner annular parts of said flat central portion and the top of 20 said heater casing, a drum supported by said flat central portion and extending through the opening thereof and through the opening in the top of said heater casing, said drum being spaced from the wall of the 25 central opening in the top of said heater casing and having openings in its side near its upper end, a draft pipe extending into said drum and being spaced from the side 30 wall thereof, said pipe also having the lower end thereof spaced from the bottom of said drum, said drum being removable with or without the inner annular part of said flat central portion and said burner being removable through the top of said heater casing and said flat central portion after 35 removing the inner annular parts therefrom.
8. The combination of a heater casing and a hover casing, each having a central opening in its top wall, a burner within 40 said heater casing larger than the opening in the latter and the opening in said hover casing, said heater and hover casings having means permitting the enlarging of said openings to allow the withdrawal of the 45 burner through the top wall thereof.
9. In a hover, the combination of a heater casing having a top wall with a central opening, a removable portion fitting into 50 said central opening and itself provided with a central opening, a hover casing spaced from said heater casing and having a central opening and a removable portion fitting into said central opening and itself provided with a central opening, a burner 55 in said heater casing of larger diameter than the openings in said removable portions, a draft pipe extending through said last-mentioned openings and supported by the removable portion of said hover casing, 60 said removable portions being adapted when removed to permit the withdrawal of the burner from said heater casing and through the wall of said hover casing.
- 35
- In testimony whereof I affix my signature. 75
ARLINGTON L. BALL.
